DEVICE FOR WAVING HAIR.

Application filed April 8, 1927, Serial No. 182,033, and in Great Britain March 11, 1927.

- This invention relates to improvements in devices for waving hair, the object being to provide a more simplified and efficient device which may be successfully used, without practical skilled experience, by the ordinary individual for waving their hair, thereby effecting a considerable saving of expense in this operation by the elimination of a skilled assistant.
- 10 In the accompanying explanatory drawing, by way of example, Fig. 1 shows a side elevation of the device of which a plan view is shown in Fig. 2, and Fig. 3 shows a cross sectional end elevation on the line III—III 15 of Fig. 1 drawn to an enlarged scale; and the same reference numbers are used for the same parts throughout. Fig. 4 is a fragmentary side elevation. Fig. 5 is a cross section on line V—V.
- 20 A pair of prongs 1 are spaced apart to form a fork and are provided with operating means such as a handle 2, there being provided a corresponding member 3 having a longitudinal ridge 4, and being hingedly 25 connected at 5 to the prongs 1, and having corresponding operating means such as a handle 6. There is formed in the member 3, at each side of the ridge 4, a longitudinal groove 7 (Fig. 3) into each of which fits 30 one of the corresponding prongs 1.
- The device is provided, or not, with an inferior conductor of heat such as asbestos 10, shown in Figs. 4 and 5, secured to the bottom of the member 3 by screw 11 or it may be compressed into a dovetailed groove 35 formed longitudinally in the bottom of the member 3 so that when the device is heated for hair waving purposes the strip of asbestos 10 will prevent scorching of the scalp 40 should the device come too close or touch the scalp. Where it is desired to stiffen the free ends of the prongs comprising the forks, the outer ends of the prongs are reinforced with a connecting bridge piece 12, shown in 45 Figs. 4 and 5, whereby greater rigidity will be imparted to the prongs 1. The free ends of the prongs 1 and the corresponding member 3 are curved or inclined at 11 and 12 with each other to a point as shown and as 50 viewed from a side elevation and from a plan view whereby the device may more readily enter the hair. It will be seen in Fig. 3 that the grooves 7 are made shallow with their outer edges rounded off and that 55 the ridge 4 projects somewhat above the prongs 1. With reference to Figs. 1 and 2, the member 3 is slotted out at 13 for passage of and working of the handle 2 and the prongs 1 on the pivot 5, this construction insuring neatness with strength and rigidity. 60 Details of construction and arrangement may be varied to suit requirements without departing from the nature or scope of our present invention.
- In operating the device, the hair is well 65 combed and divided at the position desired, the device being heated as in the case of ordinary hair waving tongs. A suitable portion of the hair is then taken up with the help of a comb, and, with the prongs 1 70 open, is placed more or less diagonally across the ridge 4 over the grooves 7. The prongs 1 are then closed on the hair by pressing the handles 2 and 6 inwards and are allowed to remain so for a few seconds applying 75 gentle pressure on the hair to be waved all the time. In closing the prongs 1, care must be taken that the hair does not lie at right angles to the ridge 4 but crosses it obliquely in the way the wave is required. 80 When the device is removed, it will be found that a ridge has been formed in the hair together with a half wave on each side of the ridge. This process is repeated along the 85 same piece of hair, or strand of hair, at distances depending on the size of the wave required, the comb being used to lead and hold the hair in the required direction in zig-zag fashion to impart the desired wave form to the hair. This must be done as the 90 prongs are closing on the hair and before it is firmly held, and so the inclination of the strands of hair across the ridge 4 is changed in direction alternately for each ridge and each half wave on each side of the 95 ridge 4 and so resembling the ridge and half wave on each side as imparted to the hair by an expert waver with the ordinary hair waving tongs. But even an expert hair waver could not do this operation on his 100 own hair with the ordinary hair waving tongs which require various skilful movements by the skilled operator who must see that the hair is being waved, whereas the device according to our invention does not 105 need any of the other skilled movements except closing in on the hair which is being directed by the comb in the manner specified, so that our device can be effectively and 110 conveniently and economically used by the

ordinary unskilled individual, man or woman, for waving their own hair.

Having described our invention, we claim:—

5 1. A device for waving hair comprising a flat member rounded or tapered to a point at one end to facilitate its insertion into the hair having an integrally formed ridge tapering to a narrow blunt edge rounded 10 at the pointed end of said member, two narrowly spaced prongs, means hingedly connecting said prongs to said member at the unpointed end thereof, said prongs being adapted to be moved to fit one at each side of 15 said ridge and to be moved about said hinged means away from the ridge and means for operating said member and prongs.

2. A device for waving hair comprising a flat member rounded or tapered to a point 20 at one end to facilitate its insertion into the hair having an integrally formed ridge tapering to a narrow blunt edge rounded at the pointed end of said member, two narrowly spaced prongs, means hingedly connecting said prongs to said member at the unpointed end thereof, said prongs being adapted to be moved to fit one at each side 25 of said ridge, having their free ends chamfered to correspond with the rounded edge 30 of the ridge and to be moved about said hinged means away from the ridge and means for operating said member and prongs.

3. A device for waving hair comprising a flat member rounded or tapered to a point 35 at one end to facilitate its insertion into the hair having an integrally formed longitudinal ridge tapering to a narrow blunt edge rounded at the pointed end of said member, 40 two narrowly spaced prongs, means hingedly connecting said prongs to said member at the unpointed end thereof, said prongs being adapted to be moved to fit one at each

side of said ridge and to be turned about said hinged means away from said ridge, 45 means on the side of said member opposite the ridge for protecting the scalp from the heated member, and means for holding said prongs against said ridge.

4. A device for waving hair comprising 50 two members, hinging means connecting said members, together like scissors, one member having its one end formed with a flat outer part lying in a diametrical plane of the hinge, and an inwardly projecting narrow 55 and high ridge perpendicular to the flat part and having the other end fashioned as a handle and the other member having its one end formed with two narrowly spaced prongs adapted to fit against the flat part 60 with one prong on each side of the ridge and to be moved about the hinging means away from the other member and having the other end fashioned as a handle.

5. A device for waving hair comprising 65 two members, hinging means connecting said members together like scissors, one member having its one end formed with a flat outer part lying in a diametrical plane 70 of the hinge tapered to a point at its extremity, and an inwardly projecting narrow and high ridge perpendicular to the flat part rounded to a point at its outer extremity, and having the other end fashioned 75 as a handle and the other member having its one end formed with two narrowly spaced prongs adapted to fit against the flat part with one prong on each side of the ridge and to be moved about the hinging means away from the other member and 80 having the other end fashioned as a handle.

Signed by us this 25th day of March, 1927.

CHARLES BUDINA.
PATRICK JAMES TRODDYN.
